CLAIM

The ornamental design for a food waste disposer housing, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of the first embodiment of the food waste disposer housing;

FIG. 2 is a front elevational view of the first embodiment of the food waste disposer housing;

FIG. 3 is a rear elevational view of the first embodiment of the food waste disposer housing;

FIG. 4 is a left side elevational view of the first embodiment of the food waste disposer housing;

FIG. 5 is a right side elevational view of the first embodiment of the food waste disposer housing;

FIG. 6 is a top elevational view of the first embodiment of the food waste disposer housing;

FIG. 7 is a bottom elevational view of the first embodiment of the food waste disposer housing;

FIG. 8 is a front perspective view of the second embodiment of the food waste disposer housing;

FIG. 9 is a front elevational view of the second embodiment of the food waste disposer housing;

FIG. 10 is a rear elevational view of the second embodiment of the food waste disposer housing;

FIG. 11 is a left side elevational view of the second embodiment of the food waste disposer housing;

FIG. 12 is a right side elevational view of the second embodiment of the food waste disposer housing;

FIG. 13 is a top elevational view of the second embodiment of the food waste disposer housing; and,

FIG. 14 is a bottom elevational view of the second embodiment of the food waste disposer housing.

(Continued)

The features shown in broken lines in FIGS. 1-14 illustrate environmental features that form no part of the claimed design.
